UNITED STATES PATENT OFFICE.

EMIL GRAF, OF NEW YORK, N. Y.

STRENGTH-TESTING AMUSEMENT DEVICE.

Application filed January 7, 1922. Serial No. 527,722.

To all whom it may concern:

Be it known that I, EMIL GRAF, a citizen of the Republic of Switzerland, and a resident of New York, in the county of New York and State of New York, have invented certain new and useful Improvements in Strength-Testing Amusement Devices, of which the following is a specification.

One of the objects of this invention is to provide a strength testing amusement device which will be coin controlled and to a certain extent automatic in its operation whereby it will not require the services of an operator or attendant.

Another object is to provide in a device of this character an indicating member movable against the force of gravity along a graduated scale to indicate the force of a blow struck by the fist against a suitable padded member.

A further object is to provide a means for returning a coin to the user of the machine when a blow exceeding a certain force has been struck.

With these and such further objects in view as will be apparent as the description proceeds, the invention consists in the following construction, combination and arrangement of parts hereinafter disclosed in

the specification, reference being had to the accompanying drawings forming a part hereof and wherein a preferred embodiment of the invention is shown, though it is to be understood that such changes, variations and modifications as may fall within the scope of the claims hereinafter appended are within the purview of my invention.

In the drawings,

Fig. 1 is a vertical sectional view taken on line 1—1 of Fig. 7.

Fig. 2 is a detail section on the line 2—2 of Fig. 1.

Fig. 3 is a detail section on the line 3—3 of Fig. 1.

Fig. 4 is an enlarged detail section on the line 4—4 of Fig. 1.

Fig. 5 is an enlarged detail section of the return coin magazine and manner in which the coin is delivered therefrom.

Fig. 6 is a section of the line 6—6 of Fig. 4 and

Fig. 7 is a front view of the machine on a reduced scale.

As shown in the drawings the machine is provided with a casing composed of a back wall 10, sides 11, top 13 and a bottom 14

which extends forwardly to support by means of a front piece 15 and an intermediate member 16, a horizontal table or shelf 17. Freely mounted for vertical movement in a suitable bracket 18 upon said table is a tubular shaft 19 having at its top a cup shaped portion 20 adapted to have secured therein a padded ball 21. The lower part of the shaft 19 may be guided by a shaft 22 which extends upwardly into the bore of the shaft 19 and which is preferably provided at its lower end with a flanged portion adapted to be suitably secured to a cross piece 23, extending between the members 15 and 16. The lower end of the tubular shaft 19 rests upon the end of a pivoted lever 24, the other end of said lever having pivoted thereto a vertically extending impact member 25 having at its upper end a suitable buffer or contact member 26 of rubber or other suitable material. A spring 27 normally urges the lever 24 in a clockwise direction (Fig. 1) to hold the ball 21 elevated and the member 26 lowered out of contact with the lower end of an indicating member 28 which may be constructed in the shape of an aeroplane. A suitable adjustable stop 24^a may be provided to regulate the extent of travel of the lever 24.

The member 28 is mounted for free vertical movement on a guiding member 29 which may be a wire, string, rod or other desirable material and which is suitably secured to extend from the top 13 to the table 17. A scale plate 30 is suitably graduated as shown in Fig. 7, the figures representing figuratively the height in feet of the upward flight of the aeroplane. If desired each set of characters may be given also the name of one of the well known powers or countries.

The tail of the aeroplane is provided with a spring pressed ratchet 31 which extends through a longitudinal slot 32 in said scale plate to engage with the teeth of a ratchet bar 33 provided with the angularly inclined slots 34 through which suitable securing means such as the screws 35 are passed. To the upper end of the ratchet bar a spring 36 is secured to normally hold the bar in its elevated forward position while the lower end of the bar is provided with a rearward extension which is adapted to contact with the periphery of a cam 38 mounted on a shaft 39 which is suitably journaled in the back 10 and intermediate member 16. A stop cam 40 is mounted on the shaft 39 and

is adapted to be engaged by the hooked end 43 of a stop lever 41 suitably pivoted as by means of the bar 42 within the casing. The other end of the lever 41 is directly beneath 5 a coin chute 44 which passes upwardly and forwardly to connect with the usual coin slot 45 provided in the front of the machine. The shaft 39 connected by a suitable gear train indicated generally by the numeral 46 10 with a spring motor 47 adapted to be wound by any suitable means such as the bevel gears 48 and a key not shown but preferably adapted to be attached to the shaft 49.

At the upper end of the machine a bell 15 crank lever 50 is suitably pivoted as at 51, the horizontal arm 52 of said crank extending forwardly and outwardly through the slot 32 adjacent the guide rod 29 and into the path of movement of the aeroplane 28. 20 The lower arm of the bell crank has pivotally attached thereto a pusher 53 having a thick flattened end adapted to pass freely through a slide casing 54 situated below a return coin magazine 55 as shown more 25 clearly in Fig. 5.

A spring 56 normally keeps the bell crank with the arm 52 lowered directly into the path of the aeroplane. A return coin chute 57 is situated with its mouth below the casing 54 and terminates at its lower forward end in the return cup 58.

The operation of the device is as follows:

A coin being inserted in the slot 45 travels 30 downwardly through the chute 44 and drops upon the end of the pivoted lever 41 causing the end 43 of the lever to be raised, releasing the stop cam 40 thereby permitting the cam shaft 39 to rotate under the influence of the spring motor, thus rotating the cam 38 which by its rotation presses downwardly 35 against the extension 37 of the ratchet bar 33 causing the bar to move downwardly and rearwardly by means of the inclined slots 34 and bolts 35. The ratchet bar therefore 40 will be moved out of engagement with the ratchet pawl 31 projecting from the tail of the indicating member 28, thus allowing the member 28, which we will assume has been driven upwardly to the dotted line position 45 shown in Fig. 1 by a previous operation of the machine, to fall to the full line position 50 in contact with the stop 28^a where it is in position to receive another impetus from the impact member 25. The rotation of the 55 cam shaft is then stopped after one revolution by the engagement of the hooked end 43 of the stop lever 41 with the shoulder 43^a of the stop cam 40, the cam 38 at the same time occupying the position shown in Fig. 60 3, thus allowing the ratchet bar 33 to be pulled upwardly and forwardly by the spring 36. The user of the machine then 65 delivers a blow with his fist upon the padded ball 21 causing the tubular shaft 19 to move the pivoted lever 24 and driving the impact

member 25 against the bottom of the indicating member 28, thus causing it to travel upwardly along the guide 29 with the spring pressed ratchet pawl in engagement with the ratchet bar 33. The upward extent of the travel of the indicating member will obviously be proportional to the force of the blow delivered to the ball 21 and the indicating member will be held at the upper point of its travel by the ratchet pawl. 75

If the indicating member is driven to the extreme upper end of the rod it will strike the horizontal arm 52 thus actuating the bell crank 50 and causing a coin to be delivered from the coin magazine through the chute 57 to the cup 58. 80

It will be understood that the indicating device may be made in any shape or form but I prefer to construct it in the form of an aeroplane and to provide the scale with 85 graduations the upper ones which correspond approximately to the highest altitudes attained in actual flights thereby presenting an attractive incentive to use the machine. 90

Having thus described my invention what I claim as new and desire to secure by Letters Patent of the United States is:—

1. In a device of the character described, a scale plate provided with graduations, a vertically extending guide adjacent said scale plate, an indicating member movable along said guide, a padded member adapted to receive a blow, means to transmit the force of said blow to the indicating member whereby it will be caused to travel upwardly along said guide and means to hold said indicating member at the upper point of its travel comprising a ratchet pawl a ratchet bar slidably mounted for longitudinal and lateral movement into and out of engagement with said pawl and means to normally hold said ratchet bar in engagement with said pawl. 100

2. In a device of the character described, a scale plate provided with graduations, a vertically extending guide adjacent said scale plate, an indicating member movable along said guide, a padded member adapted to receive a blow, means to transmit the force of said blow to the indicating member whereby it will be caused to travel upwardly along said guide, means to hold said indicating member at the upper point of its travel comprising a ratchet pawl a ratchet bar slidably mounted for longitudinal and lateral movement into and out of engagement with said pawl and means to normally hold said ratchet bar in engagement with said pawl and coin controlled means to move said ratchet bar out of engagement with said pawl. 110

3. In a device of the character described, a scale plate provided with graduations, a vertically extending guide adjacent said scale plate, an indicating member movable 115

- along said guide, a padded member adapted to receive a blow, means to transmit the force of said blow to the indicating member whereby it will be caused to travel upwardly along said guide, means to hold said indicating member at the upper point of its travel comprising a ratchet pawl and a ratchet bar movable into and out of engagement with said pawl, a spring motor, transmission means between said spring motor and ratchet bar, means to normally prevent rotation of said motor and coin controlled means to release said last named means.
4. In a device of the character described, a scale plate provided with graduations, a vertically extending guide adjacent said scale plate, an indicating member movable along said guide, a padded member adapted to receive a blow, means to transmit the force of said blow to the indicating member whereby it will be caused to travel upwardly along said guide, means to hold said indicating member at the upper point of its travel comprising a ratchet pawl and a ratchet bar movable into and out of engagement with said pawl, a spring motor, transmission means between said spring motor
- and ratchet bar and means to normally prevent rotation of said motor and coin controlled means to release said last mentioned means to allow said motor to actuate said ratchet bar out of engagement with said pawl whereby the indicating member will be released.
5. In a device of the character described, a scale plate provided with graduations, a vertically extending guide adjacent said scale plate, an indicating member movable along said guide, a padded member adapted to receive a blow, means to transmit the force of said blow to the indicating member whereby it will be caused to travel upwardly along said guide, means to project into the path of travel of the indicating member adjacent its maximum height of travel and a coin return device adapted to be actuated by said last mentioned means when the indicating member attains said maximum height.

Signed at New York, in the county of New York and State of New York, this 19th day of November, A. D. 1921.

EMIL GRAF.
